UNITED STATES PATENT OFFICE.

GEORGE G. WILEY, OF CHICAGO, ILLINOIS, ASSIGNOR TO STREETER-AMET WEIGHING & RECORDING COMPANY, OF CHICAGO, ILLINOIS, A CORPORATION OF ILLINOIS.

PRINTING MECHANISM FOR RECORDING DEVICES.

Application filed December 19, 1923. Serial No. 681,540.

This invention relates to that class of weighing scales known as "recording scales" and more particularly to that class of recording scales known as "track scales" which are 5 adapted to weigh cars and other vehicles during travel over the scale-platform.

The recording mechanism of this class of scales includes printing mechanism which is adapted to print, preferably upon a paper 10 tape, the weight of the load on the scale platform, and the present invention relates, specifically, to the recording mechanism independently of the details of construction of the weighing mechanism.

15 The invention has for its main object to provide printing mechanism for the weight recording means or mechanisms of such scales or other apparatus which is adapted to prevent a plurality of imprints on the 20 tape by rebounding action of the printing hammer to thereby assure clear imprints on the tape; and to means for automatically effecting travel of the inked ribbon associated with the printing and tape feeding mechanisms to insure the presentation of different 25 ribbon surface at each succeeding printing operation.

A suitable and preferred embodiment of the invention is illustrated in the accompanying drawings, wherein:

30 Fig. 1 is a vertical section through the housing for the recording mechanism of a scale of the general character above referred to, said mechanism being shown in elevation.

Fig. 2 is a vertical section on the line 2—2 of Fig. 1.

Fig. 3 is a plan-section on the line 3—3 of Fig. 1.

40 Fig. 4 is a side elevation of the motor employed for feeding the tape.

Fig. 5 is an end elevation of the same.

Fig. 6 is a detail view in elevation of a speed governor employed.

45 Fig. 7 is a sectional view of the same on the line 7—7 of Fig. 6.

Fig. 8 is a fragmentary detail vertical section on the line 8—8 of Fig. 3.

50 Figs. 9 and 10 are fragmentary detail sections on the lines 9—9 and 10—10, respectively, of Fig. 8.

Fig. 11 is a detail vertical section of the printing plunger on the line 11—11 of Fig. 3.

55 Fig. 12 is a detail view illustrative of a modification of a part of the mechanism.

The scale-beam 1 of the weighing-scale is associated in any suitable manner with the scale-platform, not shown, so that in response to load imposed upon the latter, the end-portion of said beam 1 shown in Figs. 60 1 and 2, will swing upwardly. By means of the rack-bar 2 meshing with the pinion 3 rigid with the shaft of the type-wheel 4, (Fig. 2) the latter is rotated through an arc 65 determined by the load on the platform to thereby dispose the number on said wheel corresponding to the weight in lbs. or multiples thereof, of the load on the platform, into vertical alignment with the printing plunger 5. In order that said beam 1 and 70 wheel 4 may move gradually to and not swing beyond the aforesaid position, the scale-beam 1 is associated with the dash-pot 6 which is described in detail and constitutes the subject-matter of a copending application filed Dec. 19, 1923, Serial No. 681,538. 75

The spring 7 exerts an initial pull on the beam contra to the dead-load rod, not shown, which is fully described in my copending application, filed Feb. 14, 1924, Serial No. 80 692,647.

Associated with the scale-platform is a trip device shown conventionally at 7^a (Fig. 1), usually a track-lever, which is disposed contiguous to the delivery end of said platform and which is adapted to be actuated by the moving vehicle after the latter has been fully disposed on the scale-platform for a sufficient period of time to have permitted the type-wheel 4 to attain the above-mentioned position ready to receive the blow of the printing plunger 5. The rod 7^b (Fig. 1) is actuated by said trip-device and is operatively connected with the ratchet associated with the ratchet-wheel 8 (Fig. 95 3) for rotating the same through a given arc, which, in this instance, is one-eighth of a revolution. The ratchet 8 constitutes a part of the mechanism actuated by the passage of a car over a track lever associated with the scale-platform for resetting the printing plunger of the present mechanism following tripping thereof to record the car-weight as the first wheel of the latter is about to leave the scale platform, said 100 ratchet being here shown only to establish association between the weighing mechanism per se and the weight recording mechanism herein more particularly illustrated and described. The ratchet wheel 8 is rigid with 110

the cam 9 and disk 10, both of which are adapted for what is termed a "two-cycle" mechanism, meaning that it is adapted for weighing cars or other vehicles, having only 5 two pairs as distinguished from four or six pairs of wheels. Each pair of wheels of the vehicle will actuate the track lever as they pass over the same and the mechanism which includes the ratchet 8, cam 9 and disk 10, 10 must be designed so that as the first pair of wheels actuates the trip-device, the cam 9 is turned to a position to release and cause an impulse of the printing plunger and to thereafter, during succeeding impulses of the trip-device by succeeding pairs of wheels of the vehicle, effect an automatic resetting of 15 the printing plunger and associated elements, to normal or initial position. The details of construction of the trip-device and 20 the mechanism associated therewith, except in so far as the cam 9 is concerned, forms no part of the present invention, but constitutes the subject-matter of a copending application, filed Feb. 14, 1924, Serial No. 692,647. 25 It will be understood, of course, that if the cars or other vehicles to be weighed have four pairs of wheels each, the mechanism will be "four-cycle" and in that case the cam 9 would have only two diametrical- 30 ly opposed points of greatest radius; whereas, if the mechanism is six-cycle said cam 9 may have only one such point, but the ratchet 8 would have only six teeth in that case or a multiple of six for each additional 35 such point of the cam 9. The number of recesses 11 in the periphery of the disk 10 will always accord with the number of teeth of the ratchet 8. A spring-held lever 12 carrying a roller adapted to engage in the recesses 11, is associated with the disk 10 which is rigid with the ratchet 8, and serves 40 to hold the latter yieldingly in the position to which it is moved successively, said lever 12 constituting no part of the present invention. 45

Associated with the cam 9 is a reciprocable plunger 13 mounted in suitable guides. It is provided at one end with a roller 14 which bears upon the periphery of the cam 50 9 under the constant tension of the spring 15 (Fig. 3). On one side of said plunger 13 is a pin or roller 16 against which one arm of a bell-crank lever 17 normally bears, by reason of the tension exerted by the 55 spring 18 associated with its other arm, the said lever 17 being pivotally supported upon a rigid frame element. The last-named arm of said lever 17 engages in a slot in the printing plunger 5 for projecting the latter against the peripheral face of the type-wheel 4. 60

The plunger 5 is movable in the guide 19 from which the bifurcated projection 20 extends. Pivotally supported between its 65 ends in said projection 20 is a trip-lever 21,

the lower end of which is normally maintained by means of a spring 22, in the path of travel of the projecting portion of a shoe 23 mounted on the lower end of the plunger 5. The upper end portion of said lever is disposed in the path of travel, in one direction, of a pin 24 mounted on the plunger 13, said pin also constituting the pivot of a pawl 25 maintained, by means of a spring 26, in engaging relation to the 75 ratchet wheel 27.

The plunger 5 (Fig. 11) has a control bore extending from its lower end into the slot in which the lever 17 engages, the lowermost end of said bore being threaded to 80 receive the screw 28 which secures the shoe 23. A light compression spring 29 is supported upon the inner end of the screw 28 and bears upon the lever 17.

The portion of the pin 24, which is adapted to trip the lever 21, is normally spaced from the latter so that when the cam 9 is rotated through an eighth of a revolution (in the instance illustrated) and the plunger 13 thus caused to move toward the axis of 85 said cam 9, the lever 17 will retain its normal position until approximately the moment that said plunger 13 attains the limit of its spring-actuated stroke, by the movement of the lower end of the lever 21 out 90 of the path of the shoe 23. It will be noted (Fig. 11) that there is a very appreciable space between the lower wall of the slot in the plunger 5 and the opposed face of the lever 17 engaging therein, so that the plunger 95 is free to move to a greater extent than said lever 17 against the action of the spring 29. A stop 17^a is provided to limit the pivotal movement of the lever 17 as the plunger 5 is released, the pin or roller 16 having moved out of the path of the short arm of lever 17 before the latter is tripped. Thus the lever 17, through the agency of 100 the spring 18, imparts an impulse to the plunger 5 sufficient to cause the upper end 105 of the latter to strike the face of the type-wheel 4. The lever 17 in itself does not move the plunger a sufficient distance, but instead imparts a momentum which will act to compress the spring 29 and therefore 110 quickly retract the plunger after the blow. There ensues a sharp rebound, which is emphasized by the action of the spring 29, which causes the upper wall of the slot to 115 strike the upper face of the lever 17 and impart an impulse thereto against the action of the spring 18. This causes a rebound of the plunger 5 toward the type-wheel which is, however, insufficient in force 120 to overcome the resistance of the spring 29 and thus a second blow upon the type-wheel 125 is prevented.

The ratchet 27 is rigidly associated with the ribbon take-up reel 30 which causes a short length of ribbon to be unwound from 130

the reel 31 which is manually rotatable, by means of the crank 32, to retrieve the ribbon from the reel 30 when the pawl 25 is disengaged from the ratchet 27. The ribbon 33 (an inked typewriter ribbon or the like) is trained over idle rolls 34 to cause a portion of the same to be disposed in a substantially horizontal plane between the face of the type-wheel 4 and the plane of travel 10 of the paper tape 35 through what may be termed the printing plane, said ribbon and tape traveling in relatively transverse directions.

The tape 35 (Figs. 2 and 3) is unwound 15 from the roll 36, suitably rotatably supported, upon which an idle roll 37 bears at a point somewhat in advance of the point at which it would normally leave the roll 36, by reason of its being trained over the more 20 elevated idle roll 38, said roll 37 being disposed at the end of a swinging support 39 and gravity actuated so that, following the unwinding of a length of tape from the roll 36, during which (by reason of sudden tension 25 on the tape) said roller 37 would be lifted, it will serve to unwind a short length of tape from the roll 36 to constitute what may be termed "slack", but which is actually a low-tension length which is preferable to slack.

From said roll 38 the tape 35 passes over an inclined plate 40 and an idle roll 41 associated therewith. It is then trained over an idle roll 42, which, in the instance illustrated, is adapted to make a complete revolution following each printing operation and is, therefore, so formed that its peripheral face is about one-half cylindrical and one-half polygonal, the last-named portion 40 presenting, preferably, two equal faces disposed substantially perpendicularly to each other.

Said roll 42 is rigid with a cam 43 having a spiral face presenting a radial shoulder 44 connecting the terminals of the spiral. Said shoulder 44 is normally engaged with the projection 45 at one end of the trip-lever 46, pivotally supported between its ends and held in the aforesaid position by means of the spring 47. The shoulder 44 is disposed substantially in the diametric plane separating the cylindrical from the polygonal portion of the face of the roll 42 and is disposed diametrically opposite a pair 55 of pins 48 (Fig. 5) projecting from the face of said roll for perforating the tape 35.

The latter is connected with the motor actuated take-up roll 49 which is so located relatively to the normal position of the roll 42 and cam 43 as to maintain the tape 35 trained over the sharp corner formed at the junction of the flat-face portions of said roll 42, the latter coacting with the pins 48 to prevent the tape from slipping under the influence of the constant tension exerted by

the take-up roll 49. The shaft 50 of the latter carries the spur pinion 51 (Fig. 3) which meshes with the spur gear 52 associated, in a well-known manner, as in a clock, with the spring 53 which actuates it 70 and is adapted to be "wound up" by means of the crank 54. Rigid with the spur-pinion 51 is a spur-gear 55 which meshes with a pinion 56 (Fig. 4) on the governor shaft 57 carrying the radial arms 58 (Figs. 5 and 6) on which brake-shoes 59 are freely reciprocable, the latter being normally maintained at approximately the outer limits of their movement by means of the springs 60. Normally one, at least, of said brake-shoes 80 59 is in contact with the cylindrical surface of the annular flange 61 of the motor frame and thus, in addition to the normal inertia of the motor parts, a very sudden acquisition of momentum by the take-up roll upon tripping the lever 46 will cause said brake-shoes 59 to be thrown outwardly by centrifugal force to bear sufficiently on said flange 61 to retard the speed of rotation of the said take-up roll. The speed of rotation 85 of the take-up roll 49 is limited by the brake-action of the shoes 59 under the influence of the centrifugal force which causes them to bear more forcibly against the surrounding flange as the speed of rotation of the shaft 90 57 increases. Owing to the small radial dimensions of the idle-roll 42, and the proportionately larger and constantly increasing diameter of the tape-roll wound upon the take-up roll 49, the rotation of the latter is 100 never in excess of and is usually only a part of a revolution for each complete revolution of the idle-roll 42. Consequently, said roll 49 could not, even independently of the retarding action of the brake or governor mechanism, acquire any great degree of momentum, though that might become sufficient to exceed the tension-strength of the tape 35 in the absence of frictional retard.

The trip-lever 46 is adapted to be actuated by the hammer-element 62 (Fig. 1) pivotally secured, by means of the screw 63, to the lever 17 adjacent the pivot of the latter. One end of said hammer-element 62 is offset away from, but to extend substantially parallel with the arm of lever 17 engaging in the slot of the plunger 5 and is of such length as to terminate contiguously to the end of said arm. The short end of the hammer-element 62 terminates in an inclined surface or shoulder which normally abuts, by gravity, against the hub 64 of said lever 17, which constitutes a stop to limit the pivotal movement of said hammer-element in one direction relatively to the latter.

One end portion of said trip-lever 46 is disposed in the path of the longer-end portion of said hammer-element 62 which, by the sudden movement and stopping of the bell-crank lever upon tripping the lever 21, 120 125 130

acquires a momentum which causes it to swing relatively to the lever 17 and impart a tripping impact to the lever 46. Thereupon the idle-roll 42 makes its revolution. 5 Following the tripping of the lever 21 as the cam 9 is given its primary impulse, the printing stroke is imparted to the plunger 5 and the tape 35 is then set in motion. The type-wheel is again free to rotate as the 10 plunger 5 does not maintain the ribbon 33 in contact therewith to retard it. The function of the spring-actuated stroke of the plunger 13 is now completed and it is then ready to be reset. As soon as the second (in 15 this instance, the last) pair of wheels of the car actuates the track-lever (not shown) to effect another one-eighth revolution of the cam 9, the said plunger 13 is reset against the action of the spring 15 and during this 20 return movement the pawl 25 actuates the ratchet 27 to effect movement of the ribbon 33. The bell-crank lever 17 is repositioned by the pin 16 and thereby the printing plunger 5 and trip-lever 21 are also 25 returned to the position shown in Fig. 1 and the whole mechanism is now ready for the next succeeding operation.

The idle-roll 42 is shaped as shown when it is desired to effect travel of the maximum 30 length of tape 35 between printing operations and may be varied in contour to adapt it for feeding fractions of said maximum length. This would necessitate a corresponding variation in the cam 43 as particularly illustrated in Fig. 12.

While it is believed that the operation of the mechanism will be fully understood from the foregoing description, the following résumé may not be superfluous.

40 Following the rotation of the typewheel 4 by the beam 1 under the influence of the load on the scale-platform whereby the weight indicating number on the type-wheel corresponding to the weight of the load, is 45 brought to oppose the plunger 5, the moving load actuates the aforesaid track-lever, thereby causing the cam 9 to be rotated through one-half the arc separating the point of contact of the roller 14 therewith from the next 50 succeeding similar point.

The spring 15 causes the plunger 13 to move toward the axis of the cam during this partial rotation of the latter and this causes the pin 16 to move away from the engaging arm of the bell-crank lever 17, thereby rendering the latter free to be actuated by the spring 18, this actuation following tripping of the lever 21 by the pin 24 and effecting a printing blow of the plunger 5 55 against the face of the type-wheel 4 through the tape 35 and ribbon 33, to thereby effect imprint of the weight indication on said tape 35.

The actuation of the bell-crank lever 17, 60 as aforesaid, causes it to hit the stop 17^a,

before the plunger 5 attains the upper limit of its movement, and thus causes the hammer-element 62 to trip the lever 46 at approximately the instant that the plunger 5 imparts the printing-blow. Thereupon 70 the motor effects short travel of the tape 35. The resetting of plunger 13 and associated parts and the movement of the ribbon then occurs to complete the whole cycle of operations. 75

It will be obvious, of course, that the details of construction of the embodiment shown and described, are capable of variation and are, therefore, to be regarded only as exemplary of a suitable embodiment of 80 the invention without limitation to specific details, except in so far as the latter are included in the invention as defined in the appended claims.

I claim as my invention:

1. In a recording scale, record-printing means including a reciprocable plunger provided with a slot, a spring housed in said plunger and projecting into said slot, a spring-actuated lever engaging in said slot 90 and engaged with the spring housed thereby for maintaining said plunger normally at one limit of its movement relatively to said plunger, a stop for limiting the movement of said lever in the direction to move said plunger to effect printing of a record to a point less than sufficient to maintain said plunger at the limit of its movement in said direction, whereby the spring housed by said plunger coacts with said lever to effect partial retraction of said plunger following its actuation by said lever, said actuation being partly against the retarding action of said housed spring.

2. In a recording scale, the combination 105 of a printing means for printing weight records on a tape and including a type carrying member and a normally latched plunger adapted when released to be projected against said member to print a 110 record, a normally latched spring controlled shifting device for affecting, when released, the projecting of the plunger, means arranged within the plunger and coacting with said device to provide for the rebound 115 of the plunger, a latching means for normally holding said plunger in a predetermined position against the projecting action of said device, and a combined releasing and setting mechanism common to said device and means.

3. In a recording scale, the combination 125 of a printing means for printing weight records on a tape and including a type carrying member and a normally latched plunger adapted when released to be projected against said member to print a record, a normally latched spring controlled shifting device for affecting, when released, the projecting of the plunger, means arranged 130

- within the plunger and coacting with said device to provide for the rebound of the plunger, a latching means for normally holding said plunger in a predetermined position against the projecting action of said device, a combined releasing and setting mechanism common to said device and means, a guide for said plunger, and said device and means connected to said guide.
- 10 4. In a recording scale, the combination of a printing means for printing weight records on a tape and including a type carrying member and a normally latched plunger adapted when released to be projected against said member to print a record, a normally latched spring controlled shifting device for affecting, when released, the projecting of the plunger, means arranged within the plunger and 20 coacting with said device to provide for the rebound of the plunger, a latching means for normally holding said plunger in a predetermined position against the projecting action of said device, a combined releasing and setting mechanism common to said device and means, a guide for said plunger, said device and means connected to said
- guide, and a stop carried by said guide for said device.
5. In a recording scale, in combination, 30 a slotted printing plunger, a guide therefor, a shoe carried at one end of the plunger, a spring controlled latching lever pivotally carried by the guide and engaging with the shoe to maintain the plunger normally in 35 a retracted position, a normally latched spring controlled shifting lever for and extending through the slot of the plunger, and means for shifting said levers from normal position to provide for the operation of the 40 plunger.
6. In a recording scale, in combination, 45 a slotted printing plunger, a guide therefor, a shoe carried at one end of the plunger, a spring controlled latching lever pivotally carried by the guide and engaging with the shoe to maintain the plunger normally 50 in a retracted position, a normally latched spring controlled shifting lever for and extending through the slot of the plunger, and a reciprocating member for alternately releasing and setting said levers.

GEORGE G. WILEY.
